EM 004562171-0001 * 12/2017

Primary Examiner — Paula Allen Greene

(74) Attorney, Agent, or Firm — Wayne V. Harper

(57) **CLAIM**

The ornamental design for a wireless earphone, as shown and described.

DESCRIPTION

FIG. 1 is a back view of a wireless earphone showing my new design;

FIG. 2 is a front side perspective view thereof;

FIG. 3 is a left side view thereof;

FIG. 4 is a right-side view thereof;

FIG. 5 is a top view thereof;

FIG. 6 is a top view thereof; and,

FIG. 7 is a back side perspective view thereof.

The broken lines are only for environmental purposes and form no part of the claimed design.
